CLAIM

The ornamental design for a conveyor slat member or similar article, as shown and described.

DESCRIPTION

FIG. 1 is a perspective view of a conveyor slat member showing my new design;

FIG. 2 is an end view thereof;

FIG. 3 is a top plan view thereof taken along line 3—3 in FIG. 2;

FIG. 4 is a bottom plan view thereof taken along line 4—4 in FIG. 2;

FIG. 5 is a side elevational view thereof taken along line 5—5 in FIG. 3; and

FIG. 6 is a side elevational view thereof taken along line 6—6 in FIG. 4.
